United States Patent Office

Des. 197,073
Patented Dec. 10, 1963

197,073

PORABLE BAR

Norman H. Woolley, 642 Skyland Drive,
Sierra Madre, Calif.

Filed June 18, 1962, Ser. No. 70,574

Term of patent 14 years

(Cl. D33—19)

Fig. 1.

Fig. 2.

Fig. 3.

Fig. 4.

FIG. 1 is a top plan view of a portable bar, showing my new design.

FIG. 2 is a front elevational view thereof.

FIG. 3 is an end view.

FIG. 4 is a perspective view of the portable bar.

The opposite end is similar to the end that is illustrated. I claim:

The ornamental design for a portable bar, substantially as shown and described.
